UNITED STATES PATENT OFFICE.

JOHN P. ADOLFSON, OF CHOKIO, MINNESOTA.

CURRY-BRUSH.

1,103,644.

Specification of Letters Patent. Patented July 14, 1914.

Application filed March 14, 1913. Serial No. 754,295.

To all whom it may concern:

Be it known that I, JOHN P. ADOLFSON, a citizen of the United States, residing at Chokio, in the county of Stevens, in the State of Minnesota, have invented certain new and useful Improvements in Curry-Brushes, of which the following is a specification.

This invention relates to improvements in curry brushes for horses and its object is to produce such a brush mounted upon a rotary shaft journaled in a frame which is provided with a canvas casing to collect the dust and dirt; said casing being provided with an opening or outlet for said dust and dirt and means for forcibly ejecting said dust and dirt therethrough.

With the foregoing and other objects in view the invention consists in the combination and arrangement of parts to be herein-after fully described in the following specification, pointed out in the claims and illustrated in the accompanying drawing which forms a part of said specification and in which—

Figure 1 is an end elevation of my improved curry brush. Fig. 2 is a side elevation. Fig. 3 is a section taken on line 3—3 of Fig. 2. Fig. 4 is a section taken on line 4—4 of Fig. 1.

Like reference characters indicate corresponding parts throughout the several views.

My curry brush comprises a frame formed of end members 1, 1 connected by an integral member 2 and provided with a handle 3 connected thereto by links 4, 4. To the frame member 2, curved braces 5 are secured to the ends of which a pair of oppositely disposed adjustable guides 6 are secured by set screws 7 and said curved braces are also connected to auxiliary braces 8 that extend to the frame members 1. In the frame members 1 and in a bearing 10 pivoted thereto a rotary shaft 11 is journaled upon which the brush 12 is mounted and said shaft is further provided with a cog wheel 13 that meshes with a large cog wheel 14 the axle of which is journaled in a bearing 15 carried by the frame and said wheel 14 is provided with a handle 16 by which it is rotated.

The frame of the brush is covered with canvas 17 which is secured thereto and to the braces 5, 5, and the auxiliary braces 8 which canvas forms a dust receptacle between the 55 brush and frame member 2; said canvas in this portion being provided with a door or vent 18 hinged as at 19 and with a leaf spring 20. Pressure upon the sides of the canvas will compress said spring 20 and 60 eject the dust and dirt as from a bellows through the door or vent 18.

In operation the handle is grasped in one hand and the brush moved over the animal while the handle 16 is rotated performing 65 the currying operation.

The spring 20 extends from side to side of the canvas sack and retains the same in open position and full of air. When the ends of the spring are pressed together by the operator 70 the canvas sack is partially closed and some of the air ejected which forces the dust out of the sack.

What is claimed is:—

1. In a curry brush, a frame provided 75 with a handle, a rotary brush provided with actuating means mounted in said frame, a canvas covering for said frame forming a dust receptacle, a vent formed in said canvas covering and flexible means secured to 80 said canvas covering for normally holding it extended whereby compression of the flexible means forcibly ejects the dust through said vent.

2. In a curry brush, a frame provided 85 with a handle, a rotary brush provided with actuating means mounted in said frame, a canvas covering for said frame forming a dust receptacle, a vent formed in said canvas covering and a spring disposed in said 90 canvas covering for normally holding it extended whereby compression of the spring forcibly ejects the dust through said vent.

In testimony that I claim the foregoing as my own I have hereto affixed my signature 95 in the presence of two subscribing witnesses.

JOHN P. ADOLFSON.
